UNITED STATES PATENT OFFICE.

EARL A. WESCOTT AND EDMOND R. BRISTOL, OF MINNEAPOLIS, MINN.

CAR-BRAKE.

SPECIFICATION forming part of Letters Patent No. 340,748, dated April 27, 1886.

Application filed September 29, 1885. Serial No. 178,506. (No model.)

To all whom it may concern:

Be it known that we, EARL A. WESCOTT and EDMOND R. BRISTOL, both of Minneapolis, in the county of Hennepin, and in the State of Minnesota, have invented certain new and useful Improvements in Car-Brakes; and we do hereby declare that the following is a full, clear, and exact description thereof.

Our invention relates to atmospheric car-brakes, and will be fully described hereinafter.

In the drawings, Figure 1 is a plan view of a car-truck to which our invention is applied. Fig. 2 is a side elevation of the same. Fig. 3 is an end view, and Figs. 4 and 5 are details.

15 A is the truck-frame, and B are the pedestal-braces. B' is the main supply-pipe, and C are branches, each of which leads to a short pipe, C', on the truck on each side of and parallel with the main supply-pipe. These short 20 pipes are provided at each end with a cock, c, from which projects a lever, c', to the outer end of which is connected a post or rod, D, by means of a hanger, d. This rod D is adapted to slide in guides D' and D'', that project in from the pedestal brace and are suspended in the upper guide, D', by means of a pin, d', or a shoulder, so that while the rod will be free to move upward it can drop down but a certain distance.

30 Instead of connecting the lever c' positively with the rod D, as shown in Figs. 1 and 3, we may have it project over the upper end of the rod, as shown in Fig. 2.

The lower ends of the rods D' on each side 35 of the truck are connected by a longitudinal beam or buffer, E, which is preferably convexed on its under side, where it is provided with fender-plates E—one at each end and one at the middle; but instead of this construction we may provide each rod with a

40 buffer-wheel, F, similar to that shown in Fig. 5, confining each wheel to the lower end of the rod by means of a bolt, f, in such a manner as to leave it free to revolve on a horizontal plane.

45 A portion of the pipe C is made flexible, as shown in Fig. 3, to permit the truck to turn on its king-bolt without affecting the brake-connection.

The operation of our device is as follows: 50 The beams E, when the car is in place on the track, are suspended directly over the rails, and therefore should an axle break or a misplaced switch be encountered, or should any other accident happen which would cause 55 either one of the wheels to leave the track, the falling of the car would bring about contact between a beam, E, and the rail, and the result would be a lifting upon either one or more of the rods D', and the opening of the 60 cock c, which latter would permit the air in the supply-pipe to escape and thus cause the setting of the brakes. The distance between the beam and rails is sufficient to insure against any trifling obstruction on the rails 65 setting the brakes; but such a mishap as this is almost impossible when wheels F are used instead of beams E, as a wheel on coming into contact with an obstruction would be revolved by it and would force it out of the way. 70

Our device is adapted for use on all known styles of trucks. It will be observed that the foot of the beam projects beyond and on either side of the path of the wheel, and, therefore, it is impossible for the wheel to leave the rail 75 without bringing the post or foot in contact with it.

Having thus fully described our invention, what we claim as new, and desire to secure by Letters Patent, is—

80 1. The combination, with the air-pipes of an atmospheric brake provided with valves, of a truck having a series of vertically-operating rods hung in guides thereon, the upper end of each rod connected directly with the 85 levers of an air-pipe valve, and longitudinal beams secured to the lower ends of said rods, as set forth.

2. The combination, with the air-pipes of an atmospheric brake provided with valves, 90c of a truck having a series of vertically-operating rods, the upper end of each rod connecting with an air-pipe valve, and longitudinal beams convex upon their under sides and secured to the lower end of said rods, as set forth. 95

3. The combination, with the air-pipes of an atmospheric brake provided with valves, of a truck having a series of inwardly-pro-

jecting guides upon its pedestal brace, a series of rods vertically operative in said guides and connected to the air-pipe valves, and longitudinal beams having their respective ends each secured to a rod and provided upon their under faces with fender-plates, as set forth.

In testimony that we claim the foregoing we have hereunto set our hands, at Minneapolis,

in the county of Hennepin and State of Minnesota, in the presence of two witnesses.

EARL A. WESCOTT.
EDMOND R. BRISTOL.
